UNITED STATES PATENT OFFICE

2,514,613

SKIRT

Aurora Elroy Thurston, New York, N. Y., assignor
to Majestic Specialties, Inc., Cleveland, Ohio,
a corporation of Ohio

Application January 14, 1947, Serial No. 721,996

4 Claims. (Cl. 2—211)

1

This invention relates to a skirt of new and improved construction and, more particularly, to a skirt of the wrap-around type.

It is an object of the invention to provide a wrap-around skirt which may be easily and quickly adjusted in position by the wearer while eliminating any unsightly discontinuities and bulges such as are encountered in skirts of conventional design having side slits or plackets.

Another object of the invention is the provision of a skirt of the character described having an inner front portion and an overlapping outer front portion together with a pair of wings or bows extending forwardly from the side seams of the skirt and adapted to be tied in bow fashion across said inner and outer front portions.

A further object of the invention is the provision of a skirt of the character described having wings or bows, which skirt may be worn in a variety of positions about the body of the wearer with the bows at the front, back, sides of the wearer or in positions intermediate therebetween.

Another object of the invention is the provision of a skirt of the character described which will have a neat and graceful appearance and which may be produced at low cost.

The foregoing objects together with additional objects and advantages will be readily apparent in the course of the following detailed description taken in connection with the accompanying drawings, which illustrate a preferred embodiment of the invention, and wherein:

Fig. 1 is a view of a skirt embodying the features of the invention adjusted in position about the wearer with the bows or wings at the front or rear of the wearer;

Fig. 2 is a view similar to Fig. 1 but with the bows or wings at the side of the wearer;

Fig. 3 is a view of the skirt partially folded before final adjustment and with the bows or wings spread out;

Fig. 4 is a plan view of the unfolded skirt and illustrates the disposition of the fastening devices;

Fig. 5 is a sectional view taken on line 5—5 of Fig. 3, but with the outer front panel removably secured to the inner front panel of the skirt;

Fig. 6 is an enlarged detailed view illustrating one manner of removably securing the outer front panel to the inner front panel of the skirt.

Referring now to the drawings in detail, the skirt comprises a rear panel 10, an inner front panel 11 and an overlapping outer front panel 12 and a pair of side seams 13 interconnecting said rear panel 10 with inner front panel 11 and outer front panel 12 respectively. If desired, a pair of auxiliary rear panels 10A of downwardly increas-

2

ing width as indicated in Fig. 4, may be employed to give the skirt a flaring effect. This latter feature, however, is entirely conventional and does not form part of the present invention.

A reinforcing waistband 14 of any suitable material may be provided inside the top of the skirt in the usual manner. The free edge 11' of the inner front panel 11 is provided at its top with fastener elements 15A which cooperate with fastener elements 15B secured to outer front panel 12 adjacent side seam 13. Fastener elements 15A and 15B may be of the snap-fastener type or any other suitable type. In any case, fastener elements 15A and 15B serve to removably secure the inner free edge of inner front panel 11 to outer front panel 12 adjacent side seam 13 thereof. The free edge 12' of the outer front panel 12 is provided at its top with fastener elements 16A which cooperate with fastener elements 16B affixed to inner front panel 11 adjacent side seam 13. Fastener elements 16A and 16B may be of the hook-and-eye type, the snap-fastener type or any other suitable type and serve to removably secure outer front panel 12 in overlapping position with respect to inner front panel 11. Since outer front panel 12 overlies inner front panel 11 in the final adjusted position of the skirt, it is desirable to run the waistband 14 only from the free edge 11' of inner front panel 11 and around the skirt to the region of fastener elements 15B secured to outer front panel 12, as shown in Fig. 5. This arrangement eliminates a double thickness of waistband at the front of the skirt and precludes any bunching or bulging.

The skirt is further provided at its top with a pair of wings or bows 20 preferably secured to and extending from each of the side seams 13 and adapted to extend across the front of the skirt. Bows 20 are preferably of sufficient length to extend across inner front panel 11 and overlapping outer front panel 12 in the adjusted position on the wearer and to be tied in bow fashion, as illustrated in Figs. 1 and 2. The particular shape and contour of bows 20 may of course vary from that illustrated in the drawings.

In actual use the skirt is wrapped about the wearer with inner front panel 11 underlying outer front panel 12, the inner free edge 11' being removably secured to outer front panel 12 adjacent side seam 13 by means of fastener elements 15A and 15B. Outer front panel 12 is next overlapped upon inner front panel 11 and removably secured thereto by means of fastener elements 16A and 16B. Bows 20 are next extended across inner front panel 11 and overlapping outer front panel 12 and tied in bow fashion.

Removal of the skirt is easily effected by reversing the order of operations. It is important to note that the skirt may be adjusted and worn in a variety of positions upon the wearer with bows 20 tied in bow fashion either at the front, back or sides of the wearer or in positions intermediate therebetween to suit the individual tastes of the particular wearer.

Since certain additional modifications may be made in the skirt of my invention, it is intended that all matter contained in the foregoing description and shown in the accompanying drawings be interpreted merely as illustrative and not in a limiting sense.

I claim:

1. A skirt of the wrap-around type comprising a rear panel, an inner front panel, an outer front panel, said rear panel being interconnected with said inner and outer front panels by means of side seams, said outer front panel being sized to overlap said inner front panel when said skirt is worn, at least one pair of cooperating fastening elements located at the waist line of said inner front panel and said outer front panel, and positioned to removably secure said outer front panel to said inner front panel in its overlapping relationship thereto, and a pair of flat vertically-disposed wing elements having inner edges respectively attached to said side seams, the upper ends of said inner edges being aligned with the upper edge of the skirt, each of said wing portions having a tapering lower edge extending from said inner edge to a relatively narrow free outer edge, each of said wing portions being appreciably longer than the width of said outer front panel, the free ends thereof thus adapted to be tied in a bow at the upper central portion of said outer front panel, said wing members, when tied, covering and concealing said fastening elements, and said lower edges of said wing members tapering upwardly from said side seams to said bow.

2. A skirt of the wrap-around type comprising an inner front panel, an outer front panel, a rear panel, and a pair of flat wing members, said inner front panel and said outer front panel being connected to opposite sides of said rear panel by means of side seams, said inner and

outer front panels having respective fastening elements positioned to removably attach said outer front panel in overlapping relationship to said inner front panel, said wing members being vertically disposed on opposite sides of said skirt and having inner edges respectively secured to said side seams, each of said inner edges extending vertically from the waist band of the skirt to a point at the hip region thereof, each 10 of said wing portions decreasing progressively in width from said inner edge to a relatively narrow free outer edge, said wing portions being sufficiently long to enable the free outer ends thereof to be tied in a bow at the center of said outer front panel when said front panel is in its overlapping position with respect to the inner front panel.

3. A skirt according to claim 2 in which the upper edge of each wing member is shaped to conform with the waistline of said skirt when 20 the wing members are tied together at the center of said outer front panel, said wing members in this position covering and concealing said fastening elements.

4. A skirt according to claim 2 in which the upper edge of each wing member is shaped to conform with the waistline of said skirt when the wing members are tied together at the center of said outer front panel, said wing members in the position covering and concealing said fastening elements, and in which the lower edge of each wing member tapers upwardly from the inner edge to the outer edge thereof, said lower edge sloping upwardly from its respective side 30 seam to the bow at the center of the outer waist panel when the skirt is worn.

AURORA ELROY THURSTON.
